UNITED STATES PATENT OFFICE.

JOSEPH C. WHITE, OF NEW YORK, N. Y., ASSIGNOR TO AUTOMATIC PARCEL DELIVERY COMPANY, OF SAME PLACE.

STORE-SERVICE SYSTEM.

SPECIFICATION forming part of Letters Patent No. 250,025, dated November 22, 1881.

Application filed November 28, 1879.

To all whom it may concern:

Be it known that I, JOSEPH C. WHITE, of the city, county, and State of New York, have invented a Store-Service System, of which the following is the specification.

My invention is a system of store-service which accomplishes automatically the work now performed in mercantile establishments by messengers generally known as "cash-boys" or "cash-girls."

In the drawings forming part of this specification, Figure 1 is an elevation showing the counters and desk of a store and with appliances for carrying out my invention. Fig. 2 is a plan in section on the line 1 2, Fig. 1.

The common practice in retail stores is to provide the salesman or attendant at each station, counter, or section of a counter with a cash-book or blanks upon or in which entries of sales and prices are made, to be then handed to the cash-boys, (either with or without the goods sold,) and by them carried to the cashier's desk or packing office, table, or station for record and adjustment of the change, and, if required, the packing and checking of the goods sold. The change, if any, is then returned by the cash-boys (together with the goods, if the custom of the store so requires) to the salesman, and is by him delivered to the customer, who has waited therefor. This plan, in practice, is full of vexations, delays, and loss of time to both salesmen and customers, especially when the store is crowded. Carelessness and mistakes on the part of the boys also frequently lead to disputes and further loss of time, and altogether the plan now in vogue has proved to be very unsatisfactory as well as costly, the annual outlay for wages alone in a large retail store amounting to many thousands of dollars.

My invention affords a simple and effective automatic system of conveyance between the salesmen and the cashier's or packer's desks, whereby the cash with its memorandum, either with or without the goods, may be carried to the cashier or packing-clerk, and returned to the salesman who sent it, and without the delays, expense, and annoyance incident to the present mode.

In carrying out my invention three things

are essential: first, an inclined way leading 5 from a counter or station to the clerk's desk; second, an inclined way leading from the desk back to said counter; and, third, a series of carriers traveling between each salesman and the clerk's desk. With such an arrangement 5 of devices each attendant may, by means of the proper carrier, forward the matter to be sent to the clerk's desk, where the desired record is made, and the clerk may then return the matter to the party who forwarded it, the whole 6 being effected more easily and quickly than a lad can make his way through a crowded store, without possibility, of misdelivery, at a fraction of the cost involved in the means now used.

The appliances used and their construction may vary according to circumstances, one arrangement being illustrated in the Letters Patent granted to me on the 11th day of November, 1879. The said patent shows the ways, 7 consisting of two rods or rails, B C, inclined in opposite directions, and extending in straight, waved, or curved lines, parallel to each other, over the various counters, E, to and from the main desk, station, or table A. These rails 7 are situated within reach of the attendants, or of suitable implements, by which carriers (each attendant having one or more of the same) can be placed on the rail inclined toward the desk. The carriers are constructed to receive and 8 hold the memorandum-books, cash, parcel, or other matter, and are provided with friction-wheels, so that they will move readily by gravity along the rails. The carriers belonging to the several attendants may be marked to indicate the party sending them, and the matter to be sent to the desk by any party is placed by him in one of his carriers, and the latter is put upon the rail inclined toward the desk, to which it will pass readily. The clerk returns 9 the change, book, or other matter sent to the desk by placing it in the carrier, depositing the latter on the rail inclined toward the position of the salesman, to whom it will pass to be arrested at its destination by hand, or by 9! means of a stop-pin properly arranged to detain the carriers pertaining to that particular salesman and no others.

If desired, turn-outs may be arranged to shunt each carrier at the counter from which it was sent, so that those behind it may pass farther n.

The carriers may be moved by clock-work, by traveling belts or bands with friction-catches, or otherwise; or the ways may consist of tubes or bands, belts, or cables passing around pulleys and provided with hooks or catches for supporting the carriers.

I do not claim the particular features of any of the arrangements above specified, as they may form subjects of separate applications for Letters Patent.

I claim—

The within-described system of store-service, consisting of an inclined way or ways leading from the stations of the salesmen to a main desk or station, an inclined way or ways leading from the desk to the said stations, and carriers adapted to be supported and conveyed by said ways from either station to the desk and back to said station, substantially as set forth. 20

In testimony whereof I have signed my name to this specification in the presence of two sub- 25 scribing witnesses.

JOSEPH C. WHITE.
